UNITED STATES PATENT OFFICE.

FRANK. W. WOOD, OF BALDWIN, MAINE.

WATER-WHEEL.

SPECIFICATION forming part of Letters Patent No. 440,085, dated November 4, 1890.

Application filed January 11, 1888. Serial No. 260,463. (No model.)

To all whom it may concern:

Be it known that I, FRANK. W. WOOD, a citizen of the United States, residing at Baldwin, in the county of Cumberland and State 5 of Maine, have invented certain new and useful Improvements in Water-Wheels, of which the following is a specification.

My invention is a turbine wheel, in which part of the guides or blades against which the water impinges in passing through the wheel are made rigid and part pivoted or movable, the movable blades or guides being automatically adjusted according to the resistance of the wheel due to the amount of 15 work which it is performing.

In the accompanying drawings, which illustrate my invention; Figure 1 represents a plan view of the invention. Fig. 2 shows a side elevation with the guides raised. Fig. 3 shows 20 a section on line $x-x$ of Fig. 1.

In the drawings I have represented the wheel as made with four fixed and four movable guides or blades, but this number is arbitrary and may be varied at pleasure within 25 reasonable limits. The hub a is connected to the rim b by means of fixed blades c , which are inclined from top to bottom, substantially as shown. The lateral walls of the blades are formed in the inside by the hub, which, 30 with the number of blades shown, is rectangular. On the other or outside the wall of the blade is formed in part by the inner face of the rim and in part by an upturned flange of the blades, as shown at d , this flange joining the rim. The upper edges of the fixed blades are substantially in radial lines and are preferably beveled or thinned down to an edge. The spaces between these four fixed blades without any further device would form 35 a wheel with blades for the downward passage of the water on the general principle of construction and with the same general effect as in water-wheels heretofore known. The spaces, however, between the blades are longer. Each 40 of these is a sector of a circle struck from the center of the wheel, with the inner angle removed on a line at right angles to the radius which passes through the center of the blade, and in the center of the curved face,

directly opposite each other, are the trunnions e , e , on which the movable blades turn. The parts are fitted as shown, so that when the movable blades lie flat or in a closed position, they form a plain closed upper surface of the wheel, which will receive the weight of the 55 water without effect.

The movable blades are connected to a sleeve F by means of rods g , which are pivoted at their lower ends to the ears h on the movable blades, the upper ends being pivoted 60 to the sleeve. The sleeve has a circumferential groove l , by means of which it may be raised. When the movable blades are closed, they will not be opened by the pressure of the water, as that operates equally on both 65 sides of the pivots, and there is besides the weight of the collar and rods all on one side; but by slightly raising the collar the upper ends of the blades are raised and the upper entrance of the water-passages opened. If 70 the wheel is running light, with but little resistance, the wheel runs with the water and the blades remain only slightly raised. If, however, the resistance or work of the wheel be increased, the force of the water will raise 75 the movable blades until they are in equilibrium, and then the passages are opened to their greatest dimensions.

I have described the wheel as located in a horizontal position, but this position is not 80 essential to its action. The wheel is to be mounted in bearings, as such wheels usually are, and the shaft is adapted to be connected in any well-known way with the machinery which it is to turn. The sleeve is splined on 85 its shaft, so as to turn therewith, to have free vertical movement, and it may have any suitable connection whereby it may be raised to start the wheel.

I claim as my invention—

1. A water-wheel consisting of a hub and rim and fixed blades located between the hub and rim, in combination with pivoted blades located in the space in the fixed blades adapted to close the passages between the fixed blades 95 and provided with means for turning the movable blades and opening the passages for the water, all substantially as described.

2. A water-wheel consisting of a hub and rim and fixed blades located between the hub and rim, in combination with pivoted blades located in the space in the fixed blades adapted to close the passages between the fixed blades and provided with a sleeve splined upon the shaft of the water-wheel, and piv-

oted rods connecting the movable blades to the sleeve, all substantially as described.

FRANK. W. WOOD.
